SPLITTING MACHINE

Charles Edwin Hood, Lynn, Mass., assignor to
 United Shoe Machinery Corporation, Paterson, N. J., a corporation of New Jersey

Application March 29, 1935, Serial No. 13,716

32 Claims. (Cl. 12—17)

This invention relates to splitting machines and is herein illustrated as embodied in a machine having a matrix into which a portion of the work is forced during the splitting operation.

5 In the manufacture of a certain type of shoe, an outsole blank is split into an insole having an opening in its forepart and an outsole having in its forepart a projection which is the counterpart of the opening in the insole, the machine 10 of the present invention being particularly adapted to perform this operation. In machines which employ a knife to which the blank to be split is fed while engaged by a matrix, it is essential that the blank be properly alined with 15 the matrix before it is engaged and split. To this end there is provided, in accordance with one feature of the present invention, gages the co-operating members of which are normally held apart to permit a blank to be placed between them upon a table, and means responsive to the 20 placing of the blank for causing the gages to close upon the blank and aline it with the matrix. In the illustrated construction the splitting mechanism is a knife and a pair of rolls, one of which 25 is a matrix roll having two matrices so that two blanks, for example a right sole blank and a left sole blank, may be split in a single operation, the rolls making one revolution and coming to rest in blank-receiving position. The sole blanks 30 are placed upon a feed table provided with two pairs of gages for each blank—a pair of rear-part gages and a pair of forepart gages. The members of the respective pairs are normally held apart, but are closed upon their respective 35 blanks to aline the blanks with their respective matrices when the blanks are placed upon the table with each blank between the members of its respective gages. The longitudinal positions 40 of the two blanks are determined by other gages against which the toe ends of the blanks are thrust when the blanks are placed upon the table. Consequently, when the pairs of side-gages have closed upon the blanks, said blanks 45 are properly alined with their respective matrices and in proper position to be engaged by the rolls. When the sole blanks have thus been located, rotation is imparted to the rolls and the feed table moves toward the splitting mechanism.

In machines of this kind, it is desirable to 50 mount the rolls in such manner that they may be quickly and accurately adjusted into different positions with respect to the knife. According, then, to another feature of the invention, the rolls are mounted on pivoted carriers, and 55 means engaging the carriers on the other side

of the rolls from the pivots are provided for adjusting the carriers about their pivots. In the illustrated construction, this adjusting means takes the form of slide rods, one mounted in each carrier, said rods having formed on their sides inclined surfaces which contact with inclined surfaces on stationary members, so that when the rods are moved longitudinally they are moved bodily sidewise and thus swing the roll-carriers about their pivots.

The sole blanks, which are to be split into insoles and outsoles, are frequently of non-uniform thickness; and when any such blank is split into two pieces, one of these pieces will also have variations in its thickness. It is preferable, if variations in thickness are to occur in one of the two articles which result from the splitting operations, that such variations should appear in the outsole. According, then, to another feature of the invention, each blank passes through the machine with its grain side, from which the outsole is to be split, in contact with the matrix roll and with its flesh side, from which the insole is to be split, in contact with the presser or matrix roll, the last-named roll being held from movement away from the knife while the matrix roll is permitted to yield to inequalities in the blank.

These and other features of the invention, including certain details of construction and combinations of parts, will be described as embodied in an illustrated machine and pointed out in the appended claims.

Referring now to the accompanying drawings, Fig. 1 is a view of the front of the machine looking in the direction indicated by the arrow in Fig. 4;

Fig. 2 is a section on the line II—II of Fig. 1;
 Fig. 3 is an elevation of the right-hand end of the machine as shown in Fig. 1;

Fig. 4 is an elevation of the left-hand end of the machine as shown in Fig. 1;

Fig. 5 is a section on the line V—V of Fig. 3 showing the mechanism for adjusting the rolls of the splitting mechanism;

Fig. 6 is a longitudinal medial section of the matrix roll;

Fig. 7 is an elevation of one of the removable matrix sections;

Fig. 8 is a perspective of one of the removable matrix sections;

Figs. 9 and 10 are respectively a perspective of an insole and of a corresponding outsole which result from the splitting of a sole-shaped blank;

Figs. 11, 12, and 13 are cross-sections on a

larger scale than Figs. 9 and 10 of portions of sole-shaped blanks after they have been split in various ways in accordance with the present invention;

5 Fig. 14 is a section on the line XIV—XIV of Fig. 1, showing more particularly the carrier having a flat table on which the sole-shaped blanks are placed and by which they are presented to the rolls of the splitting mechanism;

10 Fig. 14a is a detail in plan of the upper face of the bar 323 and certain parts carried by it;

Fig. 15 is a detail of the cam which first raises the carrier and then permits it to descend; and

15 Fig. 16 is a development of part of the periphery of the matrix roll, showing the mounting of the adjustable toe gage for initially positioning the sole-shaped blanks.

Referring first to Figs. 9 and 10, the machine is adapted, as has been stated, to split a sole-shaped blank in such manner as to produce an insole 200 having an opening 300 in its forepart, and an outsole 400 having in its forepart a projection 500 which is the counterpart of the opening in the insole, the shank and heel portions of 25 the sole and insole being each of a uniform thickness but with the insole thinner than the outsole. The shape and size of the opening 300 and the projection 500, as well as the thickness of the edge of the outsole 400 adjacent to the projection 30 500 and the cross-sectional shape of the margin of the insole which is adjacent to the opening 300, may be varied as desired by adjusting the rolls and by varying the shape of the matrix used to produce the insole and outsole. Figs. 11, 35 12, and 13 are cross-sections on a somewhat enlarged scale through portions of the margins of sole-shaped blanks after they have been split. In Fig. 11, the edge of the sole has the thickness of the original blank. In Fig. 12, the edge of the 40 sole is somewhat thinner. In Fig. 13, the edge of the sole is comparatively thin.

Referring to Fig. 2, the general mode of operation of the machine will be briefly described. The splitting mechanism comprises a stationary 45 knife 21, mounted in the usual manner, a matrix roll 23 and a patrix roll 25. A sole-shaped blank 100 is placed by the operator on the flat supporting surface of a table of a carrier 251 which at this time, when the machine is at rest, is in a raised position, as shown. A treadle is then depressed, whereupon the rolls start to revolve, and the carrier with its feed table starts to move down on rods on which it is slidably mounted, said table carrying a pusher 29 which holds the 55 toe end of the blank 100 against a toe gage 31 carried by the periphery of the matrix roll. After the blank has been gripped by the rolls and fed forward a certain distance, the carrier with its feed table is raised once more into the 60 position shown. The rolls make one revolution and come to rest. During this revolution, the insole and outsole of Figs. 9 and 10 are produced, fall upon an inclined chute 33 and come to rest in superposed relation against the upturned lower 65 end of this chute (Fig. 3).

The shaft of the patrix roll (Fig. 2) is rotatably mounted in alined bearings near the middle of a roll-carrier comprising two parallel arms, one of which is shown at 35 in that figure, 70 and the other at 35' in Fig. 1, said arms being pivoted at their upper ends about trunnions, one of which is shown at 37 (Fig. 2), said trunnions being integral with said arms, extending at right angles thereto and being received in alined bearings in the frame of the machine. Heavy coiled

springs, one of which is shown at 39, bear with one of their ends against the frame of the machine and with the other of their ends respectively against blocks, one of which is shown at 41, which are engaged by set screws, one of which is 5 shown at 43, said set screws being threaded respectively through bosses on the arms 35, 35'. These springs thus tend at all times to swing the arms and with them the patrix roll away from the knife 21. In order to swing these arms about 10 the trunnions 37 in opposition to the force of the springs 39 so as to adjust the patrix roll in the desired position with respect to the knife, the lower ends of the arms 35, 35' have alined bores to receive a slide rod 45 by movement of which 15 this adjustment is accomplished. Referring to Fig. 5, this slide rod 45 has two inclined faces 47, 49 which are engaged respectively by inclined faces on the ends of two pins 51, 53, said pins being slidable in sockets formed in brackets 20 which are rigid with the frame of the machine, these pins being backed up by adjustable set screws 55, 57. A coiled compression spring 59, which bears at one end against a collar 61 pinned to the rod 45 and at the other end against the 25 arm 35, tends at all times to slide the adjusting rod 45 to the right, said movement being limited by a hand wheel 63 carrying an adjusting screw 64 which is threaded into a socket in the left-hand end of the rod 45. The hub of the wheel 30 63 bears against a thrust bearing 65 which is located between said hub and a cap 67 of a sleeve 68, the right-hand end of said sleeve bearing against the arm 35. When the adjusting screw is turned in a direction to pull the rod 45 to the 35 left (away from the observer as viewed in Fig. 2), the inclines 47, 49 on the rod 45 ride up the inclines on the ends of the pins 51, 53, and the patrix roll is adjusted toward the knife (Fig. 2) against the force of the springs 39. A small rod 40 69 (Fig. 5), pinned to the rod 45 and having a stop nut 71 and a check nut threaded on its outer end, limits the extent of movement to the left of the rod 45 by contact of the nut 71 with the stationary bar 72 and prevents the rod 45 45 from being adjusted far enough to the left to cause the patrix roll to contact with the knife. The matrix roll 23 is mounted in a manner similar to that of the patrix roll just described. Referring to Figs. 2 and 5, the shaft of the matrix 50 roll is mounted in alined bearings near the middle of a roll-carrier comprising two parallel arms 73, 73' which have alined trunnions at their upper ends, one of which is shown at 75, said arms being urged at all times to swing toward the knife 55 by two heavy compression springs, one of which is shown at 77, the tension of which may be adjusted by turning adjusting screws, one of which is shown at 79. Referring more particularly to Fig. 5, the arms 73, 73' have slidably mounted 60 in alined bores in their lower ends an adjusting rod 81 which has inclined faces 83, 85 engaging respectively inclined faces on the ends of pins 87, 89 which are slidably mounted in bores formed in the frame of the machine. A coiled compression spring 91 between a collar 93 pinned to the shaft 81 and the arm 73 urges the rod to the right; and a hand wheel 95, which carries a screw threaded into the left-hand end of the rod 81, provides means for pulling the rod 81 to 70 the left to move the matrix roll away from the knife. A stop screw 97 threaded through a stationary bar 98 limits the movement of the rod 81 to the right so as to prevent the matrix roll from ever being adjusted into a position in which, dur- 75

ing the rotation of the rolls, it will strike the matrix.

Referring to Fig. 2, stop screws, one of which is shown at 98, carried by the frame are adapted to contact with bosses on the arms 13, 13' to determine the limit of possible movement of the matrix roll toward the knife and thus to prevent this roll from ever coming into contact with the knife. In the position of rest in which the parts of the machine are shown in Fig. 2, these stop screws are spaced from the bosses because the matrix roll, when brought to rest, has been moved into and is being held in a position such that its distance from the matrix roll is just slightly less than the thickness of the blank to be split. It is so held during the greater part of the splitting operation. Near the end of that operation, however, it is released so as to grip the blank more firmly and remains thus until after the split blank is ejected from the machine. After it rides off the trailing end of the split blank, the stop screws 98 prevent it from contacting with the knife. Subsequently, and before the roll comes to rest, the roll is moved into and held in the position shown, as will be explained in detail later.

Referring again to Fig. 5, and disregarding for the moment the manner in which the pins 87, 89 are supported for automatic movement at times for a purpose which will be described, it will be noted that adjustment of the rod 45 adjusts the matrix roll and holds that roll from movement away from the knife, and that adjustment of the rod 81 adjusts the matrix roll and holds it from movement toward the knife. As will presently appear, there are two matrices on the matrix roll and two patrices on the matrix roll, two sole blanks at a time being presented to the machine. Each blank is presented with its flesh side toward the matrix roll and the grain side toward the matrix roll, the matrix roll having been adjusted into a position such that its distance from the knife edge is equal substantially to the desired thickness of the edge of the sole, and the matrix roll having been adjusted into a position such that its distance from the knife edge is equal to the desired thickness of the edge of the insole. The matrix roll can not yield away from the knife but the matrix roll can yield, and consequently, if the edge of the sole-shaped blank varies in thickness, corresponding variations will appear in the edge of the sole which is split off, but the edge of the insole will be of uniform thickness. The variations in thickness at most will be small, and those in the edge of the sole will disappear during the subsequent sole edge trimming operations. On the other hand, the disadvantage of employing insoles of varying thicknesses in the manufacture of shoes will be avoided.

Returning again to Fig. 5, the mechanism for automatically moving the pins 87, 89 lengthwise at times and the reason for so doing will be described. It is desirable, when a blank is presented to the rolls, that the rolls be separated somewhat so that when rotated, they will immediately seize the blank and carry it forward. They should be so held for an interval, at least until the splitting operation is well under way, but they should grip the blank with more force near the end of the splitting operation so as to discharge the split blank. The machine comes to rest, as shown in Fig. 2, with the matrix roll positively held away from the matrix roll a distance slightly less than the thickness of the blank to be split, and is prevented from approaching nearer to the matrix roll until the splitting of

the blank has proceeded for a considerable distance. Before the end of the splitting operation, the matrix roll is freed so that the springs 71 may move it toward the matrix roll to grip the blank more firmly. This control of the matrix roll is accomplished (Fig. 5) by moving at the proper times a rod 99 which is parallel to the rod 81 and slidably mounted in the frame, said rod having inclines 101, 103 to receive inclined ends of the pins 87, 89. This rod at its right-hand end is connected by a pair of links 105 to a pivot 107 at the lower end of a lever 109. This lever (Fig. 3) is pivoted near its middle at 111 to a bracket on the frame of the machine and has at its upper end a roll 113 which runs in a cam track (Fig. 1) formed in the periphery of a cam 117. With the machine at rest, the rod 99 is in a position shown in Fig. 5 in which it occupies its extreme right-hand position and, through the pins 87, 89, is holding the matrix roll away from the matrix roll, as shown in Fig. 2. When the rolls and the cam 117 are given one revolution, in a manner presently to be described, the rod 99, during the first part of the revolution, remains in the position shown but, before the splitting operation is finished, it is removed to the left thereby permitting the matrix roll to move toward the matrix roll to grip the blank more firmly. It remains thus until the splitting operation is completed and the split blank ejected, after which it is moved back into the position shown as the machine comes to rest. The pins 87, 89 are kept from turning about their axes by spring-pressed plungers 88, 90 mounted in sockets in the pins and bearing against the inclines on the rod 81.

It has been explained that turning the hand wheels 63, 95 (Fig. 5) moves the adjusting rods 45, 81 lengthwise and adjusts the rolls toward and from the knife. In order to facilitate fine adjustments, there is associated with each adjusting mechanism a pointer and scale. Since these pointers and scales are substantially identical, only one will be described in detail. Referring to Fig. 4, the pointer 119 for the adjusting rod 45 is mounted on a stationary pivot 121 and is acted upon by a torsion spring 123 which holds its lower end at all times in contact with the end of the rod 45 (Fig. 1); said lower end extending through a slot in the sleeve 68. The upper end of the pointer 119 swings over a scale marked upon a stationary member 125. Thus, as the hand wheel 63 is rotated to slide the rod 45 in one direction or the other, the tip of the pointer moves over the scale. The other pointer 127 (Figs. 4 and 1) is similarly mounted with respect to the adjusting slide rod 81, and its tip moves over a scale on a stationary member 129.

It has been explained that when sole blanks 100 are presented to the splitting mechanism, their toe ends are placed in contact with a gage 31 mounted on the periphery of the matrix roll 23. Referring to Figs. 14 and 16, this toe gage is fast to a small segmental member 131 slidably mounted in a transverse slideway formed in the periphery of the matrix roll, said member being held in adjusted position by screws 133 the stems of which pass through slots 135 in the slide member and are threaded into the matrix roll. In order to adjust the slide member and the gage 31 about the periphery of the roll, the slide member has formed on it a small rack 137 which meshes with a small pinion 139 formed at the upper end of a pin 141 rotatably mounted in a radial bore in the roll and frictionally held from turning by a spring-pressed

plunger 143. A kerf in the top of the pin 141 is adapted to receive a screw driver by which the pin may be turned.

It is desirable to provide removable and replaceable matrix and patrinx sections for the two rolls of the splitting mechanism so that matrices and patrices of different sizes and shapes may be readily provided. Inasmuch as the matrix and patrinx sections, except for the matrices and patrices, are substantially alike and mounted in the same manner, only the matrix sections and their mounting will be described in detail. Referring to Fig. 6, the matrix roll 23 and its shaft 145 are shown, said roll having cut-away portions to receive the two matrix sections. Each matrix section 147, 149 has a peripheral surface which corresponds to that of the main portion of the matrix roll and has formed in said surface a suitable matrix, that in the section 147 being shown in perspective at 151 in Fig. 7. Each section has also a flat surface in which is formed a segmental groove 153 to fit over the shaft 145 and carries a cylindrical stud 155 which is radial to the shaft when the section is in place, and the inner end of which extends into a transverse bore in the shaft, said bore registering with a socket 157 in the body portion of the matrix roll. The shaft has a small bore 159 through its center, and the stud 155 has a bore which registers with the bore in the shaft when the section is in place. A long locking pin 163 is adapted to be thrust through the bore in the shaft and the registering bores in the pins to hold the sections in place. In order to push the sections out so that they may be readily grasped when the locking pin 163 has been withdrawn, compression springs 165 are fastened into sockets 157 by screws 167. In order to hold the locking pin 163 in withdrawn position without entirely withdrawing it from the shaft, a spring-pressed plunger 169 is adapted to engage a shoulder 171 formed by reducing the diameter of the locking pin at a locality near its inner end. Thus, when the locking pin 163 has been withdrawn from the bores in the studs 155 carried by the sections 147, 149, said sections are pushed out somewhat by the compression springs so that they may be readily grasped and removed. New sections are put in merely by pushing them into place on the matrix roll and pushing in the pin 163. The sections of the patrinx roll, one of which is shown in Fig. 8, are mounted in the patrinx roll in the same manner as the matrix sections are mounted in the matrix roll. One of the patrinx sections with its stud, together with the patrinx roll, its shaft, its locking pin and the spring which pushes the patrinx section out when the locking pin has been withdrawn, is shown in Fig. 2.

Referring to Fig. 4, the locking pin 163 of the matrix roll has fastened to its outer end a finger-hold 173, and the locking pin 175 of the patrinx roll has a similar finger-hold 177, said finger-holds facilitating the manipulation of these two pins. It is desirable that means be provided to prevent the machine from being accidentally started while either of these pins is in withdrawn position during the removal and replacement of matrix or patrinx sections. To this end, means is provided for preventing the clutch (later to be described) from being thrown in whenever either of the locking pins is in withdrawn position. For this purpose, depending fingers 179, 181 of a guard member 183 normally extend over the finger-holds 173, 177 of the locking pins and prevent them from being withdrawn. When it is desired to withdraw

them, this guard member 183 is swung up about its pivot 185 so that the fingers 179, 181 are out of register with their respective locking pins. When the guard member is thus swung up, its tail engages the outer end of an arm 187 the hub of which is fast to one end of a rockshaft 189, this being a shaft which must be rocked, clockwise as viewed in Fig. 4, to throw in the clutch. The other end of this shaft 189 is shown in Fig. 3. To it is pinned the hub of an arm 191 which, when swung to the left, releases the pin of a pin-clutch and throws in the clutch which starts the machine. Also pinned to the shaft 189 is the hub of a curved arm 193 to the outer end of which is pivoted the upper end of a treadle rod 195 to the lower end of which is pivoted a treadle, not shown, a spring of any suitable type, also not shown, being provided to maintain the treadle rod 195 normally in its upper position, as shown. Returning now to Fig. 4, it will be seen that when 20 the guard member 183 is in the position shown, the treadle can be depressed to rock the shaft and throw in the clutch; and when the guard member has been swung up to permit withdrawal of the locking pins 163, 175, the clutch can not 25 be thrown in. The guard member 183 is held in the position shown by a spring-pressed plunger 194 which passes through a bore in the guard member and engages a shallow socket in a stationary member. Another shallow socket 196 receives the end of the pin when the guard member has been swung up. This plunger 194 and its spring are shown more clearly in Fig. 1.

Referring to Fig. 3, the clutch is of the well-known pin type and will not be described in detail, since any suitable clutch may be employed. It will be understood, however, that when the arm 191 has been swung to the left to free the pin, the clutch is thrown in and rotation is imparted to the driving shaft 197 until the arm 191 is permitted to be returned by the usual treadle-rod spring, not shown, to the position shown when the driving shaft comes to rest. A friction band brake 199 of the usual type is held about a drum on the shaft by a bolt 201 and a spring 202. 40

The train of gears by which rotation is imparted to the shafts 145 and 203 of the matrix and patrinx rolls respectively will now be described. Referring to Figs. 1 and 3, there is fast to the driving shaft 197 a small gear 205 which meshes 50 with a large gear 207 fast to a shaft the axis of which coincides with that of the trunnions 75 about which the arms which carry the matrix roll are pivoted. Also fast on the same shaft with the gear 207 is a smaller gear 211 which meshes 55 with a gear 213 on the shaft 145 of the matrix roll. The same gear 211 also meshes with an idle gear 215 on a stub shaft whose axis coincides with that of the trunnions 31, said gear meshing in turn with a gear 217 on the shaft 203 of the patrinx roll. This gearing permits the arms which carry the matrix and the patrinx rolls to be adjusted in the manner which has been described about the axes of the trunnions 75 and 31 without disturbing the mesh of the gears 211, 213, 215 and 217, the gear 213 rolling on the gear 211, and the gear 217 rolling on the gear 215. In order to cause the clutch to be thrown out and the matrix and patrinx rolls brought to rest after they have completed one revolution, during which time the driving shaft 197 will have made several revolutions, there is formed on one side of the large gear 207 a cam 219 upon which rests a roll 221 carried at the outer end of an arm 223 the inner end of which is fastened to the rockshaft 189 to which is also fast, 70 75

as has been stated, the arm 191 rocking of which throws the clutch in or out. When the treadle is depressed to swing the arm 191 to the left (Fig. 3), the clutch is thrown in and the large gear 207 begins to rotate. The small roll 221 engages the high part of the cam 219 and prevents the arm 191 from swinging back into the position shown until said roll runs off from the high part of the cam 219, whereupon the arm 191 swings back and the machine comes to rest, this mechanism being so designed that when the treadle is depressed and released, the matrix and patrrix rolls make one complete revolution and come to rest.

As has been stated above, the sole-shaped blanks are placed two at a time on the flat supporting table of a carrier 251 and presented to the rolls of the splitting mechanism. Referring to Fig. 1, the machine is shown at rest with two blanks 100, indicated in dotted lines, in approximately the position they will occupy when the machine is started. These soles are not exactly in such position, since certain side gages, presently to be described, have not yet been caused to act upon them to line them up properly with their respective matrices and patrices. The carrier 251 comprises a heavy casting slidably mounted on inclined studs 253 carried by the frame of the machine which is raised into the position shown by a cam, presently to be described, then permitted by movement of the same cam to descend by gravity to present the blanks to the splitting mechanism and is then returned to the position shown. The carrier 251, in its middle portion, has a cross-sectional shape, shown in Fig. 2, and is provided with four flat bars 254, 255, 257, 259 which provide a blank-supporting table the plane of which extended passes between the rolls of the splitting mechanism. When two blanks are placed upon this table with their toe ends against the toe gage 31 on the matrix roll preparatory to being split, it is desirable that they be properly lined up with respect to their respective matrices and patrices. To this end (Fig. 1), a pair of rear-part gages and a pair of forepart gages are provided for each blank, the members of each pair of gages being held spaced apart when the machine is at rest but being caused to close upon their respective blanks when the blanks are seated on the flat surface of the table formed by the bars 254, 255, 257, 259, the blanks in being so seated engaging trip members which release the gages. Inasmuch as the two pairs of gages (rear-part and forepart) for one blank are substantially identical in construction and mode of operation with those of the other blank, only the two pairs of gages associated with the right-hand blank will be described in detail. For the right-hand blank 100, shown in Fig. 1, there are provided a pair of rear-part gages 261, 263, and a pair of forepart gages 265, 267. An ear on the gage 261 is pivoted at 269 to the lower end of the vertical arm of a bell-crank lever 271 which is pivoted to the carrier 251 at 273, the horizontal arm of this bell-crank lever having at its free end a segmental gear which meshes with a segmental gear at the free end of the horizontal arm of a second bell-crank lever 275 which is also pivoted to the carrier, and the downward extending vertical arm of which is pivoted at 271 to an ear on the gage 263. A long tension spring 279 connects the vertical arm of the bell-crank lever 271 with the vertical arm of a bell-crank lever 281, which carries one of the rear-part

gages of the other blank 100, and tends at all times to swing the vertical arms of the bell-crank levers 271, 281 toward each other. This spring thus acts always, when permitted to do so, to move into contact with the blank the rear-part gages 261, 263, as well as to cause a similar movement of the other pair of rear-part gages 305, 307. In order to cause the rear-part gages 261, 263 to maintain in all positions their parallel relation to each other, two links are provided, namely a link 283 pivoted at its lower end to an ear on the gage 261 and at its upper end to the horizontal arm of the bell-crank lever 271, and a link 285 pivoted at its lower end to an ear on the gage 263 and at its upper end to the horizontal arm of the bell-crank lever 275. The gages 261, 263 are being held spaced apart by a latch which is released by means of trip members having push buttons which are encountered and moved when the blanks 100 are pushed down upon the table formed by the flat bars 254, 255, 257 and 259. When this latch is released, the gages 261, 263 move toward each other in parallel relation under the force of the spring 279 to engage the rear part of the blank. The forepart gages 265, 267 are mounted in the same manner as the rear-part gages, being carried respectively by the depending arms of bell-crank levers 287, 289 the horizontal arms of which are geared together. Links 291, 293 are provided to maintain the gages in parallel relation at all times. A tension spring 295 connects the bell-crank lever 287 with a bell-crank lever 297 by which one of the forepart gages for the left-hand blank 100 is carried and tends, when permitted to do so, to move the gages 265, 267 toward each other by rocking the bell-crank levers 287, 289. The rear-part gages 261, 263 are being held apart because the carrier 251 is in raised position and a stop screw 299 has engaged a horizontal arm of the bell-crank lever 271 and swung it into the position shown. The forepart gages 265, 267 are being held apart by a small vertical rod 301 slidably mounted in the carrier 251, the lower end of which is pushing against the upper surface of the horizontal arm of the bell-crank lever 287, the upper end of said rod having been engaged during the previous upward movement of the carrier by a stop screw 303 which is directly behind the stop screw 299, as viewed in Fig. 1, but is shown in Fig. 14. The construction, mounting and general mode of operation of the rear-part and forepart gages for the right-hand blank 100 (Fig. 1) have been described in detail above. The rear-part and forepart gages for the left-hand blank 100 are constructed, mounted and operated in substantially the same manner, and no detailed description will be given. It will be noted, however, that the rear-part gages 305, 307 are being held apart by the engagement of a stop screw 309 with the upper surface of the horizontal arm of a bell-crank lever 311 which carries the gage 305, and that the forepart gages 313, 315 are being held apart by means of a vertical slide rod 317 the lower end of which engages a horizontal arm of a bell-crank lever 319 which carries the gage 313 and the upper end of which is in engagement with a stop screw 321 which is directly behind the screw 309 but is shown in Fig. 14a.

The stop screws 299, 303, 309, 321 are carried by a bar 323 (Fig. 14) which is pinned to the upper end of a rod 325 slidably mounted in the carrier 251. This rod is prevented from turning (Figs. 1, 3, 14a) by a small stud 324 carried

by the carrier 251, which extends up through a bore in the bar 323. This rod 325 has pinned to it a catch member 327 having a downwardly extending sleeve to receive a compression spring 329, the lower end of which bears upon a bracket which is part of the carrier 251, the rod being held down, in the position of parts shown, by a latch 331 which is pivoted to the frame of the machine at 333 and is urged to swing to the right 5 by a compression spring 335. This latch has slidably mounted in its upper portion, for a purpose which will presently appear, a contact member 337 which is acted upon by a compression spring 339, said spring being located between a bored 10 plug 341 and a collar 343 fast to the round stem of the contact member 337. This round stem extends up through the bore in the plug 341 and has a stop nut 338 and a check nut threaded upon its upper end. The latch 331 is released 15 by pressing the sole-shaped blanks 100 respectively against two push buttons 345, 347. The button 345 (Fig. 14) is fast to the outer end of a small slide rod 349 which is pivoted at its inner end to one end of a substantially horizontal bar 351, the other end of which is pivoted to the inner end of a second slide rod 353 (Fig. 1) to the outer end of which is fastened the other push button 347 against which the left-hand blank 100 is pressed by the operator. The bar 20 255 has cut-away portions in its lower edge to permit the buttons 345, 347 to be pushed in flush with the bar. With this construction, it is necessary to press the blanks 100, one against each of the push buttons, in order to cause the bar 25 351 (Fig. 14) to swing back the latch 331 and thus release the slide rod 325 and permit the spring 329 to raise the rod and thus to raise the stop screws 299, 303, 369, and 321 to release the rear-part and forepart gages (Fig. 1) and permit the long tension springs 279, 295 to move the gages into contact with the blanks 100 so as to align the blanks properly with their respective matrices. If only one of the buttons 345, 347 30 is pushed back, the bar 351 is merely moved angularly and no thrust is exerted by it to swing back the latch 331. Both buttons must be pushed back to release the latch. It may be desirable at times to present only one blank at a time to the machine and in such case pushing in only 35 one of the push buttons should free the latch and cause the gages to close upon the blank. To this end, means is provided for locking one of the push rods 353 (Fig. 2) in its inner position. This means takes the form of a set screw 332 40 threaded through a portion of the carrier 251 and adapted to engage a shallow socket 334 formed in the periphery of the push rod 353 when that rod has been pushed in. With the push rod 353 thus held, pushing in the other push rod 349 (Fig. 1) will release the latch. The carrier 251 is raised and held temporarily in the position 45 shown by a cam 357 (Fig. 15) on the shaft 75 which acts upon a roll 359 mounted on the carrier 251, the cam being shown in its position of rest in that figure.

Referring now more particularly to Figs. 1 and 14, the operation of the blank-presenting mechanism as thus far described will be given. Two blanks are placed with their toe ends against 50 the toe gage 31 on the matrix roll and pressed back against the push buttons 345, 347 to cause the bar 351 to swing the latch 331 to the left (Fig. 14) and thereby free the catch 327, whereupon the rod 325, and with it the bar 323 and its stop 55 screws, are moved up by the spring 349. Moving

the stop screws up frees the four pairs of gages to permit them to close upon and align the blanks with their respective matrices. The blanks are now positioned sidewise and lengthwise. The treadle of the machine is depressed. The rotation of the cam 357 permits the carrier 251 to slide down upon its studs 253, and this downward movement of the slide continues until the splitting operation has been partially completed, whereupon the cam 357 returns the carrier 251 to the raised position of rest shown. When the latch 331 was released by being swung to the left (Fig. 14) the catch 327 was moved up as has been described. Before the carrier 251 started to rise, the latch had swung back under the influence of the spring 335 to move its contact member 337 into the path of the rising catch member 327. Consequently, as the carrier 251 approached the upper limit of its movement, the catch member 327 engaged the contact member 337 of the latch, and upward movement of the rod 325 (which had been moving up with the carrier 251) was arrested. The upward movement of the bar 323 with its stop screws was also arrested. As the carrier 251 completed the last part of its upward movement, the stop screws in the bar 323 acted in the manner which has been described upon the bell-crank levers 275, 311, 289, and 297 (Fig. 1) to open the four pairs of gages which engage respectively the rear parts and the fore parts of the two blanks. It will be noted, by reference to the shape of the cam 357 (Fig. 15), that the carrier 251 is moved up to the extreme limit of its upward movement and is then allowed to descend a trifle so that the cam stops in such a position that, when the machine is started, the carrier will at once begin its downward movement under the influence of gravity. It is because of the shape of this cam and the consequent fact that the carrier is first moved to the extreme limit of its upward movement and allowed to descend a trifle that the spring-pressed contact member 337 (Fig. 14) is mounted in the latch 331. When the carrier has reached its upper limit of movement, the four stop screws, of which two are shown at 299, 303, have engaged their respective bell-crank levers and opened the four pairs of gages. If now the contact member 337 was rigid with the latch 331, the subsequent short downward movement of the carrier 251 to its position of rest would move the bell-crank levers away from the stop screws and permit the members of the four pairs of gages to approach one another to some extent. With the construction shown, the spring-pressed contact member 337 maintains the stop screws in contact with the bell-crank levers and holds the four pairs of gages wide open. A stop screw 360 (Figs. 1, 14, and 14a) threaded through the bar 323, by engaging the carrier 251, limits the extent of downward movement of the bar with respect to the carrier.

In order to make sure that the toe ends of the blanks 100 are in contact with the toe gage 31 (Fig. 14) before the machine is started, and to maintain them in such contact during the first part of the splitting operation, two pushers 29, one of which has been referred to in connection with Fig. 2, are provided. These pushers are formed (Fig. 1) as the inwardly bent lower ends of two downwardly extending arms of a sheet metal plate 361. This plate extends through a slot 363 (Fig. 14) in the upper end of a rod 365 and is pivoted to the rod by a headed pin 367 the stem of which passes through a hole in the plate 361 and through any selected one of a row

of holes 369 through the rod 365. This rod is slidably mounted in bearings in the carrier 251, and its lower end extends into a socket 371 in the carrier, the lower end of the rod and the socket forming a dash-pot the purpose of which will appear later. A coiled compression spring 373, located between a collar 375 fast to the rod and a part of the carrier 251, exerts a downward pressure on the rod. The rod is held up, when the parts are in the positions shown, by a lever 377 pivoted near its middle at 379 to the carrier 251, said lever engaging with one end a pin 381 carried by the rod 365 and with the other end the bottom of the downwardly extending sleeve formed on the catch member 327. In order to prevent the pusher-rod 365 from turning in its bearing, the inner end of the stem of a small screw 383, which is mounted in the carrier 251, extends into a longitudinal groove 385 formed in the rod 365.

The whole operation of the blank-presenting mechanism and the splitting mechanism will now be described. Referring first to Figs. 14 and 15, the carrier 251 is in raised position, being so held by the cam 357. The operator places two sole-shaped blanks approximately in line with their respective matrices and with their toe ends in contact with the gage 31 on the matrix roll, and pushes the blanks firmly into contact with the table formed by the spaced flat bars 254, 255, 257, 259. In doing so, the buttons 345, 347 are pushed in, and the latch 331 is swung out to free the slide rod 325 which rises under the influence of the spring 329 and thereby permits the four pairs of gages (Fig. 1) to close upon the blanks and aline them with their respective matrices. When the slide rod 325 moves up, it releases the slide rod 365 which is then free to be moved down by its spring 373. This rod 365 does not, however, move down instantly but lags by reason of the dash-pot construction at its lower end so as to make sure that the gages have closed against the opposite edges of the blanks before the pushers 29 begin to operate. The blanks are now in proper position, being alined with their respective matrices, and with their toe ends held firmly against the toe gage 31. The treadle of the machine is depressed and released, whereupon the rolls make one revolution. During the first part of the revolution, the carrier 251 slides down so as to make sure that the blanks are properly presented to and grasped by the rolls. During the latter part of the revolution, the cam 357 raises the carrier 251. As the carrier rises, both slide rods 325, 365 rise with it until the latch 331 engages the catch 327 to arrest the upward movement of the rod 325. Thereafter the upward movement of the carrier 251, since it carries with it the pivot 379 of the lever 377, raises the slide rod 365 with respect to the carrier and compresses the spring 373. The upward movement of the carrier, after the slide rod 325 has been engaged by the latch, also opens the four pairs of gages by causing the bell-crank levers, by which the members of the pairs of the gages are carried, to be rocked by means of the stop screws carried by the bar 323. The cam 357, as has been explained, raises the carrier 251 to the extreme upper limit of its movement and then permits it to descend through a short distance, the stop screws in the bar 323 being held by the action of the spring-pressed contact member 337 in position to maintain the four pairs of gages open. The parts of the blank-presenting mechanism then come to rest in the positions

shown. Returning now to the splitting mechanism, it will be recalled that when the splitting rolls are at rest, the matrix roll is being held, by means of the rod 99 (Fig. 5), the pins 87, 89 and the rod 81, at a distance from the matrix roll which is slightly less than the thickness of the blanks, but near enough to the matrix roll so that the rolls grasp the blanks and feed them firmly to the knife. The splitting operation proceeds thus until a locality near the trailing end of the blanks has been reached, when the rod 99 is slid to the left to permit the matrix roll to be forced more firmly into contact with the blanks so as to ensure that the blanks will be ejected from the rolls at the end of the splitting operation. Each of the sole-shaped blanks is split into an insole like that shown in Fig. 9, and an outsole like that shown in Fig. 10. The outsoles (see Figs. 2 and 3) fall directly upon the chute 33 while the insoles pass over the knife 21 (Fig. 2) and are directed into superposed relation upon the outsoles by a sheet metal baffle plate 387 fastened by screws 389 to the frame of the machine (see also Fig. 1).

Although the invention has been set forth as embodied in a particular machine, it should be understood that the invention is not limited in the scope of its application to the particular machine which has been shown and described.

Certain features herein disclosed are also disclosed in prior application Serial No. 748,522, filed October 16, 1934, in my name, said prior application disclosing a machine for splitting a sole blank into a complementary insole-outsole combination; and all patentable subject-matter common to that application and this one is claimed in said prior application.

Having described my invention, what I claim as new and desire to secure by Letters Patent of the United States is:

1. A machine of the class described having, in combination, splitting mechanism including a matrix, means for alining a blank with the matrix, said means comprising a table upon which the blank is placed and blank-alining gages normally held spaced apart to permit a blank to be placed upon the table between them, and means operated by so placing the blank for causing the gages to engage and aline the blank.

2. A machine of the class described having, in combination, splitting mechanism including a matrix, means for alining a blank with the matrix, said means comprising a table upon which the blank is placed and blank-alining gages normally held spaced apart to permit a blank to be placed upon the table between them, means operated by so placing the blank for causing the gages to engage and aline the blank, and means for thereafter causing the table to move toward the splitting mechanism and the splitting mechanism to operate.

3. A machine of the class described having, in combination, splitting mechanism including a matrix, means for alining a blank with the matrix, said means comprising a table upon which the blank is placed and blank-alining gages normally held spaced apart to permit a blank to be placed upon the table between them, yielding means urging the gages toward the blank, and means operated by placing a blank on the table for releasing the gages to cause them to engage and aline the blank.

4. A machine of the class described having, in combination, splitting mechanism including a matrix, and means for alining a blank with the

matrix, said means comprising a table upon which the blank is placed, blank-aligning gages normally held spaced apart to permit a blank to be placed upon the table between them, means operated by so placing the blank for causing the gages to engage and aline the blank, and means for maintaining the gages in parallel relation in all positions which they may occupy.

5. A machine of the class described having, in combination, splitting mechanism including a matrix and means for alining a blank with the matrix, said means comprising a table upon which the blank is placed, bell-crank levers having two of their arms geared together, blank-alining gages carried by other arms of the bell-crank levers, yielding means urging the bell-crank levers to swing in directions to cause the gages to close on the blank, means acting in opposition to the yielding means for normally holding the gages spaced apart to permit a blank to be placed upon the table between them, and means operated by so placing a blank for releasing the holding means to permit the yielding means to cause the gages to engage and aline the blank.

25 6. A machine of the class described having, in combination, splitting mechanism including a matrix and means for alining a blank with the matrix, said means comprising a table upon which the blank is placed, bell-crank levers having two 30 of their arms geared together, blank-alining gages carried by other arms of the bell-crank levers, yielding means urging the bell-crank levers to swing in directions to cause the gages to close on the blank, means acting in opposition to the 35 yielding means for normally holding the gages spaced apart to permit a blank to be placed upon the table between them, means operated by so placing a blank for releasing the holding means to permit the yielding means to cause the gages to 40 engage and aline the blank, and means for there-
after operating the splitting mechanism.

7. A machine of the class described having, in combination, splitting mechanism including a matrix and means for alining a blank with the matrix and for presenting the alined blank to the splitting mechanism, said means comprising a carrier movable toward and from the splitting mechanism, a table mounted on the carrier upon which the blank is placed, blank-alining gages also mounted on the carrier, means operated by movement of the carrier away from the splitting mechanism for moving the gages into spaced relation to permit a blank to be placed upon the table between them, and means operated by so placing a blank for causing the gages to engage and aline the blank.

the blank.

8. A machine of the class described having, in combination, splitting mechanism including a matrix and means for alining a blank with the matrix and for presenting the alined blank to the splitting mechanism, said means comprising a carrier movable toward and from the splitting mechanism, a table mounted on the carrier upon which the blank is placed, blank-alining gages also mounted on the carrier, means operated by movement of the carrier away from the splitting mechanism for moving the gages into spaced relation to permit a blank to be placed upon the table between them, means operated by so placing a blank for causing the gages to engage and aline the blank, and means for thereafter operating the splitting mechanism and for moving the table toward the splitting mechanism.

9. A machine of the class described having, in combination, mechanism including two matrices

for splitting two blanks at a time, and means for alining the blanks with their respective matrices, said means comprising a table upon which the blanks are placed, and blank-alining gages, a set for each blank, normally held spaced apart to permit the blanks to be placed upon the table between their respective gages, and means operated by so placing both blanks for causing the gages to engage and aline the blanks.

10. A machine of the class described having, in combination, mechanism including two matrices for splitting two blanks at a time, and means for alining the blanks with their respective matrices, said means including a table upon which the blanks are placed, a pair of blank-alining gages for each blank, a latch normally holding the gages spaced apart to permit the blanks to be placed upon the table between their respective gages, push buttons adapted to be engaged and depressed by the blanks when the blanks are placed upon the table, and mechanism connecting the push buttons and the latch constructed and arranged to release the latch only when both push buttons have been depressed.

11. A machine of the class described having, in combination, splitting mechanism including a matrix roll and a patrrix roll, a gage on the periphery of one of the rolls against which the leading end of a blank to be split is placed, means engaging opposite edges of the blank for alining the blank with the matrix, and means for thereafter operating the splitting mechanism.

12. A machine of the class described having, in combination, splitting mechanism including a matrix roll and a patrrix roll, a gage on the periphery of one of the rolls against which the leading end of a blank to be split is placed, means for rotating the rolls and for bringing them to rest with the gage in proper position to have the leading end of the blank placed against it, and means engaging opposite edges of the blank for alining the blank with the matrix prior to imparting further rotation to the rolls.

13. A machine of the class described having, in combination, a knife, rolls for advancing a blank to the knife to cause it to be split, a carrier located above the rolls for presenting a blank to the rolls, said carrier being slidably mounted for movement toward and from the rolls, and means for first raising the carrier into a position to permit a blank to be placed upon it and for thereafter releasing the carrier to permit it to descend by gravity.

14. A machine of the class described having, in combination, splitting mechanism including a matrix roll and an end gage carried on the periphery thereof and adapted to receive the leading end of a blank to be split, and means for alining the blank with the matrix, said means comprising a table upon which the blank is placed with its end in contact with said end gage, blank-alining gages normally held spaced apart to permit the blank to be placed upon the table between them, and means operated by so placing the blank for causing the gages to engage and aline the blank.

15. A machine of the class described having, in combination, a knife, a pair of rolls one of which is a matrix roll, means for rotating the rolls, means for causing the rolls to exert a yielding pressure upon a blank, means for temporarily relieving the pressure of the rolls as they arrive at blank-receiving position, a feed table, and gages for alining the blank with the matrix preparatory to presentation of the blank to the rolls.

16. A machine of the class described having, in combination, a knife, a pair of rolls one of which has a matrix, spring means for urging one of the rolls toward the other, means for rotating the rolls to cause a blank to be split by the knife, means for bringing the rolls to rest in blank-receiving position with the spring-pressed roll held away from the other roll a distance slightly less than the thickness of the blank to be split, a table upon which the blank to be split is placed, normally separated gages for alining the blank with the matrix, and means actuated by placing the blank on the table for causing said gages to close upon and aline the blank, preparatory to rotating the rolls. 5
17. A machine of the class described having, in combination, splitting mechanism including a knife and a pair of rolls one of which has a matrix, means for alining a blank with the matrix, said means comprising a table, normally separated blank-alining gages and means for causing the gages to engage and aline the blank when the blank is placed on the table, spring means urging one roll toward the other, means 10 for holding said roll away from the other roll in opposition to the force of the spring a sufficient distance to permit the leading end of the blank to be readily grasped by the rolls, means for rotating the rolls to cause the knife to split 15 the blank, and means becoming operative during the splitting operation to release the spring-pressed roll so as to cause the blank to be gripped more firmly at the end of the splitting operation and ejected from the splitting mechanism. 20
18. A machine of the class described having, in combination, means including a knife for splitting a sole-shaped blank into an insole member having an opening in its forepart and a sole member provided with a complementary projection, a chute to receive one of the members after it passes the knife, and means for directing the other member upon the one received by the chute so that the two members are in superposed relation. 25
19. A machine of the class described having, in combination, a knife, a pair of rolls including a matrix roll for advancing a blank to the knife, one of said rolls having a curved guideway in its periphery, a curved guide slidably adjustable in 30 said guideway about the axis of the roll, a gage carried by the guide and extending above the periphery of the roll in position to have an edge of a blank placed against it, said guide having formed thereon a rack, and a rotary adjusting member carried by the roll and having a pinion in mesh with the rack. 35
20. A machine of the class described having, in combination, a knife, a pair of rolls for advancing a blank to the knife, one of said rolls being a matrix roll, a gage projecting from the periphery of one of the rolls in position to have an end of the blank placed against it, means for 40 rotating the rolls, and a pusher for maintaining the blank in contact with the gage until the rolls have firmly grasped the blank. 45
21. A machine of the class described having, in combination, a knife, a pair of rolls for advancing a blank to the knife, one of said rolls being a matrix roll, a gage projecting from the periphery of the matrix roll in position to have an end of the blank placed against it, means for rotating the rolls, and a pusher for maintaining the blank in contact with the gage until the rolls have firmly grasped the blank. 50
22. A machine of the class described having, in combination, a knife, a pair of rolls one of which is a matrix roll, means for rotating said rolls and for bringing them to rest in proper position to receive a blank, a blank carrier for alining the blank with the matrix and for feeding the blank to the rolls, means for moving the carrier toward and from the rolls, blank-alining gages and a pusher mounted on the carrier, and means actuated by movement of the carrier for operating the gages and the pusher. 5
23. A machine of the class described having, in combination, a knife, a pair of rolls one of which is a matrix roll, means for rotating said rolls and for bringing them to rest in proper position to receive a blank, a blank carrier for alining the blank with the matrix and for feeding the blank to the rolls, means for moving the carrier toward and from the rolls, blank-alining gages yieldingly urged at all times to move into closed position, a spring-pressed pusher, and means operated 15 by movement of the carrier away from the rolls for separating the gages and for locking the spring of the pusher, said means being operated by movement of the carrier toward the rolls for releasing both the gages and the pusher. 20
24. A machine of the class described having, in combination, a knife, cooperating rolls, means for rotating the rolls, a carrier on which one of the rolls is mounted, a pivot on which the carrier is mounted, a spring tending to swing the carrier about said axis, and a slide rod engaging the carrier to adjust it angularly in opposition to the force of the spring. 25
25. A machine of the class described having, in combination, a knife, cooperating rolls, means for rotating the rolls, a carrier on which one of the rolls is mounted, a pivot on which the carrier is mounted, a spring tending to swing the carrier about said axis, an adjusting rod slidably mounted in the carrier and extending transversely thereof, 30 and means responsive to longitudinal sliding movement of the rod for moving the rod sidewise and thereby adjusting the roll carrier about its pivot. 35
26. A machine of the class described having, in combination, carriers mounted for pivotal movement toward and from each other about parallel axes, rolls rotatably mounted one on each carrier, a knife cooperating with the rolls, springs tending to swing the carriers about their pivotal axes, 40 and slide rods engaging the carriers to adjust them in opposition to the force of the springs. 50
27. A machine of the class described having, in combination, two arms, pivots upon which the arms are respectively mounted near one of their ends, rolls rotatably mounted respectively in the arms at a distance from the pivoted ends, means for rotating the rolls, a knife cooperating with the rolls, springs tending to swing the arms about their pivots, and slide rods engaging the arms 55 at localities more remote from the pivoted ends of the arms than are the rolls to adjust them in opposition to the force of the springs. 60
28. A roll for a splitting machine, said roll comprising a main portion and a removable section, a shaft to which the main portion is fastened, said shaft having a longitudinal bore and an intersecting transverse bore, a pin carried by the removable section and adapted when the section 65 is in place to extend into the transverse bore in the shaft, said pin having in it a transverse bore which then registers with the longitudinal bore in the shaft, and a locking pin slidable in the longitudinal bore in the shaft and extending 70
- 75 75

through the transverse bore in the pin to hold the section in place.

29. A roll for a splitting machine, said roll comprising a main portion and a removable section, a shaft to which the main portion is fastened, 5 said shaft having a longitudinal bore and an intersecting transverse bore, a pin carried by the removable section and adapted when the section is in place to extend into the transverse bore in the shaft, said pin having in it a transverse bore 10 which then registers with the longitudinal bore in the shaft, a locking pin slidable in the longitudinal bore in the shaft and extending through the transverse bore in the pin to hold the section in 15 place, and a spring acting upon the removable section to push it out when the locking pin is withdrawn.

30. A roll for a splitting machine, said roll comprising a main portion and a removable section, means for locking the removable section in 20 place, and a spring acting to move the removable section out of place when the locking means is rendered inoperative.

31. A roll for a splitting machine, said roll

comprising a main portion and a removable and replaceable section, said main portion having a cut-away portion to permit the section to be removed and replaced by moving it radially of the main portion from and toward the axis thereof, means for locking the section in place, and a spring acting to move the section out of place in a path radial to the axis of the roll when the locking means is rendered inoperative. 5

32. A machine for removing at a single cut 10 from a sole-shaped blank having a grain side and a flesh side, an insole which is all flesh and has an opening in its forepart and an outsole which is part grain and part flesh and has a complementary projection having, in combination, a 15 knife, a patrix roll and a matrix roll adapted to receive the blank and advance it to the knife with the flesh side in contact with the patrix roll, means for permitting the matrix roll to yield away from the knife while preventing the patrix 20 roll from so yielding, and means engaging opposite edges of the sole blank to aline it with the matrix and patrix.

CHARLES E. HOOD.
